UNITED STATES PATENT OFFICE.

WILLIAM G. MILLER, OF KANSAS CITY, MISSOURI.

PRESSURE-REGULATOR.

1,222,652.

Specification of Letters Patent. Patented Apr. 17, 1917.

Application filed May 27, 1915. Serial No. 30,769.

To all whom it may concern:

Be it known that I, WILLIAM G. MILLER, a citizen of the United States, residing at Kansas City, in the county of Jackson and State of Missouri, have invented certain new and useful Improvements in Pressure-Regulators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to pressure regulators, and more particularly to a device of this character which is interposed in a gas line for the purpose of reducing pressure of the gas delivered from a high pressure supply, so that it may be utilized at a materially less pressure at the opposite side of the regulator; the specific use of the gas at the lower pressure being immaterial as the device is capable of association with any of a number 20 of gas using devices or apparatus.

It is the principal object of the present invention to provide a regulator of this character to which the admission of the gas from a high pressure supply is controlled by a 25 valve, preferably of the needle type, and wherein the valve is under control of float mechanism that may be adjusted to balance at predetermined levels for various pressures.

30 It is also an object of the invention to provide a device of this character whereby gas under high pressure may be admitted to the regulator and delivered therefrom under lower pressures, varying from a fraction of 40 an ounce to any pressure less than that under which the gas is admitted from the supply.

In accomplishing these and other objects of the invention I have provided improved 45 details of structure, the preferred forms of which are illustrated in the accompanying drawings, wherein:—

Figure I is a perspective view of a pressure regulator constructed according to my 50 invention.

Fig. II is a horizontal section of the same.

Fig. III is a vertical section on the line 55 III—III, Fig. IV.

Fig. IV is a vertical section on the line IV—IV, Fig. III.

Fig. V is a detail view of a valve-seat plug.

Referring more in detail to the drawings:

1 and 2 respectively designate intake and float chambers, preferably consisting of glass cylinders arranged adjacent each other, and seated at their upper and lower ends in grooves 3—3', 4—4' in the base and top plates 5—6 respectively, with the grooves packed to seal the chambers and prevent the escape of the gas under regulation or of float liquid; the base and top plates being connected and held to the cylinders by bolts, or the like, 7, that extend through the plate flanges 8—9, outside of the cylinders.

The top plate 6 has a boss 11 thereon rising above the adjacent cylinders 1—2, and provided with a vertical bore 12 that communicates with a channel 13 leading into the top of the chamber 1; the lower end of the bore 12 being screw-threaded to carry a plug 14 having a channel 15 opening into the upper portion of the bore and having a downwardly opening tapered valve seat 16 opening into channels 13 and 15. The threaded part of the bore is preferably tapered and the plug 14 correspondingly shaped to fit its seat; the preferred construction being that wherein the plug extends across the channel 13 and seats within a socket 17 in the boss at the bottom of the channel.

With this last named construction, the plug 14 is provided with a diameter port or bore 19, intersecting the valve seat bore, in line with port 13; so that gas admitted through the plug may pass from said port 13 directly into the chamber 1. The top of the bore 12 may be sealed by a cap plug 20, and opening into a bore 21, between the cap and valve plugs, is a connection 22 for a supply pipe (not shown) which may lead to any 95 source of high pressure gas supply.

Extending downwardly between the intake and float chambers, and preferably formed integral with the top plate 6, is a standard 23; the lower end of which is preferably enlarged and extends through an opening 24 in the bottom plate 5; the bottom plate being preferably provided with a depending ring 25 that is spaced from the lower end of the standard to receive packing 26 and the lower end of the standard being screw-threaded to carry a gland 27, whereby the packing is compressed to form a seal about the standard and prevent escape of the float liquid or gas.

The bottom of the standard contains a socket 28, and depending from the stand-

ard is an arm 29 having a slot 30 therein through which a beam 31 is projected and pivotally mounted on a pin 32 that is carried by the arm and extends across the slot.

5 Pivots mounted on the beam 31 is a link 33 which extends upwardly into the socket 28 and connects with the lower end of a valve stem 34, which is slidably mounted in a channel 35 that extends through the standard and boss 11 and into the valve plug 14; the upper end of the plug having a needle point 36 that is adapted to seat in the tapered valve seat 16 and stop the flow of high pressure gas from the supply to the chamber 1.

10 The beam 31 is inclosed by a housing 37 that is preferably formed integral with the bottom plate 5 and comprises a depending ring having an inturned flange 38 forming a central bottom opening 39, through which access may be had to the beam; the opening 39 being normally closed by a plate 40 which may be attached to the bottom of the flange 38 by screws 41, and is preferably 20 provided with a guide lip 42 that lies along the edge of the flange to properly place the plate.

25 The plate is also provided with a drain aperture 43, and carries a cock 44 whereby the aperture is closed to seal the chamber, or opened when the latter is to be drained.

30 Opening through the bottom plate 5, adjacent the ring 37, are ports 45 and 46 that communicate respectively with the regulator chambers 1 and 2, so that the ring and its plate not only constitute a chamber for inclosing the regulator beam but also form a connecting chamber between the main regulator chambers 1 and 2.

35 40 One end of the beam extends beneath the port 46 and pivotally connected with that end of the beam, by a link 48, is a float rod 49 which extends upwardly into the chamber 2 and has a threaded upper end 50 for carrying a float 51, of any ordinary type, but preferably comprising a central column 52, having interior screw threads for coöperating with the threaded rod 49 to adjust the float to desired elevations along the rod, for a purpose presently described.

45 50 The float is guided in its vertical reciprocation by a post 53 which is fixed to the top of the float and extends into a closed guide pocket 54 that is removably mounted on the top plate 6, preferably by means of a screw-threaded shank 55; the diameter of the pocket being greater than that of the post, and the end of the post being provided with a ball 56 which wipes the inner surface 60 of the pocket to firmly guide the post with a minimum of lost motion and friction.

55 60 By removably mounting the pocket 54 on the top plate 6 it may not only serve as a guide for the float post but may be removed 65 to expose the post, so that the latter may be

turned to adjust the float on its screw-threaded rod 49 to determine the level within the float chamber at which the float will rise and actuate the intake control valve; the principal regulation of the valve being effected, however, by a weight 57 which is slidably mounted on the opposite end of the beam 31 and fixed in adjusted position on the beam by a set screw 58; it being apparent that the float may be adjusted by the balance 70 weight when the regulator is assembled, and that any future adjustment may be easily and quickly effected by means of the float post.

75 An outlet from the intake chamber 1 is effected through a port 59 on a valve body 60 that is mounted on the top plate 6 and provided with a tip 61 to which a pipe may be attached, the said body being preferably equipped with a dial 62 upon which the outlet pressure may be read.

80 The flow of gas through the port 59 and tip 61 is controlled by a needle valve 63 provided with a pointer 64 for indicating the volume of discharge.

85 90 In order to prevent mixture of gas under regulation with the float liquid I preferably locate a free float 63 in the intake chamber 1, so it may ride on the liquid and form a partition between the gas and liquid compartments; it being apparent that when gas is admitted to the upper portion of the chamber under sufficient pressure to overcome that of the liquid, the float will be forced downwardly onto the liquid, but that 95 the packing in the float will prevent escape of gas to the lower portion of the chamber and obviate its mixture with the float liquid. It is quite apparent, however, that while the presence of the free float may be advantageous with the regulation of some gases, it 100 is unnecessary with others, as the pressure of the gas directly on the liquid will have the same regulating effect.

105 110 In order to increase the range of the regulator so that gas may be delivered therefrom at a pressure varying but slightly from that of the supply, I provide a supplemental chamber 65 which is mounted on the top plate 6 and opens into the float chamber 2; 115 this supplemental chamber preferably comprising a glass tube bearing at its opposite ends against the plates 66 and 67, which are held together and to the ends of the tube by elongated bolts 68 to form an air-tight 120 seal at the top of the tube; the top plate 67 being provided with a cock 69 whereby air within the tube may be released from the tube to relieve the pressure within the float chamber.

125 130 In describing the use of the regulator we will presume that the parts are constructed and assembled as described, and the regulator connected with a high pressure gas supply and with a device for utilizing the gas

under pressure lower than that in the supply. We will also presume that the chambers contain float liquid that will support the regulating and partition floats at predetermined levels, and that the float has been positioned on the rod 50 to insure its rising only when the float liquid has reached a predetermined level in the chamber 2.

Under these conditions, and prior to the admission of high pressure gas to the regulator, the weight of the regulating float will hold the arm of the beam that is connected with the valve stem downwardly, so that the needle valve is open to admit gas to the intake chamber. When the gas is turned on by manual control (not shown) it flows into the intake chamber through the open valve and expands so that its pressure is materially reduced. Continued intake of the gas, however, develops a pressure on the free float within said chamber that forces the float downwardly onto the liquid in the bottom of the chamber 1; the displacement of the liquid carrying same through the housing 37 into the chamber 2 and lifting the float 51. As the float 51 rises it lifts the beam 31 and valve stem 34 until the needle valve 36 closes the intake port 15 cutting off the supply of high pressure gas. When the supply is cut off, the gas in the chamber 1 is relieved through the outlet 59, and as the gas passes off through the outlet the pressure is taken from the top of the float 63 and the float liquid tends to rise and seek its level in the intake chamber. As the level of the liquid lowers in the chamber 2 the float 51 drops and opens the valve so that the high pressure gas may again flow into the intake chamber.

It is apparent that when the regulator is first brought into use the parts will fluctuate to open and close the valve, but that after a short time a constant position of the valve is assumed that will admit a continuous flow of high pressure gas in such a restricted quantity as to constantly feed the low pressure device.

When the supply to the low pressure device is to be varied, the needle valve 63 is moved to increase or decrease the area of the valve opening to the degree indicated by the pointer 64. This variation in the supply to the low pressure device requires automatic regulation of the intake valve through the float mechanism.

When it is desired to use the gas at low pressure, the unbalanced levels of the liquid alone are depended upon for the regulation, and the cock 69 on the supplemental chamber 65 is open so that liquid in chamber 2 is exposed to atmospheric pressure.

If gas is to be used at high pressure the cock 69 is closed so that when the float liquid rises in the chamber 2 it does so against pressure of the contained air. As gas is ad-

mitted to the intake chamber the float liquid is displaced and tends to rise in the float chamber. As the liquid rises in the float chamber it is resisted by the contained air and must compress the air in order to gain a level where it will lift the float and shut off the supply to the intake chamber.

Having thus described my invention, what I claim as new therein, and desire to secure by Letters-Patent, is:—

1. A regulator comprising an intake control valve, a pivotally mounted beam operatively connected with the valve, a rod on said beam, a float having threaded mounting on the rod, and a weight on said beam for counterbalancing the float.

2. A regulator comprising an intake control valve, lever mechanism for actuating the valve, a float adjustably mounted on the lever mechanism, a post on said float extending to the exterior of the regulator, and a pocket removably mounted on the regulator and normally inclosing the projected portion of said post.

3. A regulator comprising an intake control valve, lever mechanism for actuating the valve, a float adjustably mounted on the lever mechanism, a post on said float extending to the exterior of the regulator and having a guide ball at its free end, and a pocket removably mounted on the regulator and having interior guiding contact with the float post ball.

4. A regulator comprising separate intake and float chambers and a supply conduit leading to the top of the intake chamber, a conduit connecting the lower portions of said chambers, a valve seat in the supply conduit, a beam pivotally mounted in the connecting conduit, a valve rod connected with said beam and having a head coöperating with the valve seat to control supply to the intake chamber, a float rod on said beam projected into the float chamber, and a float adjustably mounted on said rod.

5. A regulator comprising separate intake and float chambers and a supply conduit leading to the top of the intake chamber, a conduit connecting the lower portions of said chambers, a valve seat in the supply conduit, a beam pivotally mounted in the connecting conduit, a valve rod connected with said beam and having a head coöperating with the valve seat to control supply to the intake chamber, a float rod on said beam projected into the float chamber, a float adjustably mounted on said rod, a post on said float extending to the exterior of the regulator, and a pocket removably mounted on the regulator and inclosing and guiding the float.

6. A regulator comprising separate intake and float chambers and a supply conduit leading to the top of the intake chamber.

ber, a conduit connecting the lower portions of said chambers, a valve seat in the supply conduit, a beam pivotally mounted in said connecting conduit, a valve rod connected with said beam and having a head coöperating with the valve seat to control supply to the intake chamber, a float rod on said beam projected into the float chamber, a float adjustably mounted on said rod, and a counter-balancing weight on said beam.

7. A regulator comprising separate intake and float chambers, a top plate inclosing the upper ends of said chambers and comprising intake and delivery port conduits leading to and from the upper portion of the intake chamber, a bottom plate inclosing the lower ends of said chambers and having openings therefrom, a depending housing on said plate inclosing the openings and having an opening in its lower part, a removable cap normally closing the housing opening, a valve seat in the intake conduit, a valve stem having a head at one end for coöperating with said seat, and having its opposite end projected into said housing, a beam pivotally mounted in said housing and connected with the valve stem, a rod on said beam projecting into the float chamber, and a float adjustably mounted on said rod.

8. In a regulator comprising an intake control valve, a float chamber, a float in said chamber operatively connected with said valve, and a supplemental chamber having open communication with said float chamber and having a valve controlled opening leading to atmosphere, for the purpose set forth.

40 9. In a regulator comprising an intake control valve, a float chamber, a float in said chamber operatively connected with said valve, a supplemental air pressure chamber opening into the float chamber 45 above the float, and a valve for controlling pressure in said supplemental chamber.

10. The combination with separate intake

and float chambers and a supply to the intake chamber, connection between the intake and float chambers, lever mechanism 50 in said connection, a valve operatively connected with said lever mechanism and adapted for controlling the supply to the intake chamber, a float in said float chamber operatively connected with said lever 55 mechanism, and a supplemental chamber opening to the float chamber above the float.

11. The combination with separate intake and float chambers having suitable connection, of means for supplying fluid to the intake chamber, a float in the float chamber, a valve for controlling flow of fluid from said supply means to the intake chamber, lever mechanism connected with said float and said valve, and a supplemental chamber 65 opening to the upper portion of the float chamber, whereby raising of the float by fluid passed to the float chamber from the intake chamber is facilitated by exhaust of air from the float chamber to the supplemental chamber to lessen resistance of the float and permit closing movement of the valve.

12. The combination with separate intake and float chambers having suitable connection, of means for supplying fluid to the intake chamber, a float in the float chamber, a valve for controlling flow of fluid from said supply means to the intake chamber, lever mechanism connected with said 80 float and said valve, a supplemental chamber opening to the upper portion of the float chamber, whereby raising of the float by fluid passed to the float chamber from the intake chamber is facilitated by exhaust 85 of air from the float chamber to the supplemental chamber to lessen resistance to the float and permit closing movement of the valve, and a valve on the supplemental chamber for regulating the escape of fluid 90 therefrom.

In testimony whereof I affix my signature.

WILLIAM G. MILLER.
